R. G. RECH

PROGRESS CHART

Filed Dec. 10, 1923

UNITED STATES PATENT OFFICE.

RAYMOND G. RECH, OF SYRACUSE, NEW YORK.

PROGRESS CHART.

Application filed December 10, 1923. Serial No. 679,871.

To all whom it may concern:

Be it known that I, RAYMOND G. RECH, a citizen of the United States of America, of Syracuse, in the county of Onondaga, in the State of New York, have invented new and useful Improvements in Progress Charts, of which the following, taken in connection with the accompanying drawings, is a full, clear, and exact description.

10 This invention relates to a progress chart adapted to be used more particularly in large manufacturing establishments as a means for informing those interested as to the preparation, progress and completion of the manufacture of various articles entering into a particular machine although it is equally applicable for use in any other relation where it is desired to keep a record of the progressive stages of development of any 20 particular line of work.

In the extensive manufacture of machines of a certain type, each involving the use of a considerable number of parts, it is customary to carry in stock a sufficient quantity 25 of raw materials for a given number of machines depending upon the capacity of the plant and economic working conditions, the stock on hand being distributed to various departments for such operations and 30 processes of finishing as may be necessary to enable them to be easily and quickly installed in their respective places in the assembling or finishing department.

It is well known that some of the parts 35 require a greater number of operations sometimes in different departments than other parts, and in order that the work of each department may progress without delay or loss of time in each department, it is 40 highly important that the raw materials and unfinished work be kept up in proper ratio of production or completion to keep the assembly room at full working capacity.

These duties usually devolve upon what is 45 commonly known as the production manager and his assistants, and the main object of my present invention is to provide a progress chart composed of sections, each designated by a suitable title representing a particular part of a machine, and each section 50 provided with a plurality of strips rela-

tively adjustable endwise one over the other and each strip bearing graduated indicia cooperating with one end of a next superposed strip whereby the production manager or his assistant may at any time, adjust any one or the other of the strips of each section to give a reading which will indicate the various stages of progress of manufacture of articles under the title of that particular section from the stock on hand or on order, to the finished article so that the production manager or any other person interested, may quickly determine by an examination of the chart, the exact progress made in the completion or finishing of the articles under any one or the other of the titles and also gives exact information as to the stock on hand or on order, and if on order, the quantity due for a given total production of machines, the number under process of manufacture, and the number actually finished from which may be determined the amount of stock necessary to order for a continuation of the process or the necessity of urging the delivery of the raw materials on order and not yet delivered.

Another object is to distinguish adjacent strips, one from the other by contrasting colors, whereby the observer may visualize immediately the rate of manufacture of any particular article through the various stages of completion by simply comparing the lengths of the exposed portions of the strips of any one section and in like manner, may determine the rate of manufacture of the different articles in various stages of production by comparing the lengths of the exposed portions of the strips of any one section with those of the other sections.

A further object is to provide suitable guides for the strips of each section whereby said strips may be readily adjusted endwise by hand as the work upon the articles of that particular section progresses.

Other objects and uses relating to specific parts of the device will be brought out in the following description.

In the drawings;—

Figure 1 is a front elevation of a progress chart showing, in this instance, three sections partly broken away.

Figure 2 is an enlarged longitudinal sectional view, partly broken away taken on line 2-2, Figure 1.

Figure 3 is an enlarged transverse vertical sectional view taken on line 3-3, Figure 1.

The chart shown is designed to show the progressive development of a plurality of, in this instance three, articles of manufacture and therefore, comprises a series of 10 three parallel guides or sections —1— of substantially equal length arranged edge-wise one upon the other and formed intermediate their ends with return bends —1'— so that the opposite ends of the guides 15 extend in the same direction and terminate in substantially the same transverse plane each section being designated by a different title such as M 1001 base, M 1002 Lf. front leg, M 1003 Rt. front leg, printed or 20 otherwise impressed upon suitable cards —2— which are removably inserted in guide plates —3—, the latter being secured to the front faces of the sections —1— near the return bend —1'— with their inner ends in 25 vertical alinement to form a fixed index —4—. If desired, these guide plates —3— may be rigidly united along their adjacent edges to each other and rigidly secured by 30 brazing or otherwise, to the sections —1— to assist in supporting said sections.

The outer ends of the plates —3— may be hinged at —5— to any suitable support as 35 —6— to permit the entire chart to be swung in a horizontal plane to different angles as may be most convenient for observation by the users.

The printed title in the plates —3— represent the names of different articles to be 40 operated upon and adapted to enter into the construction of machines of a certain type, each using one or more of said articles.

The front portions of the guides —1— extend horizontally in the same direction from their respective title plates —3— and 45 terminate in the same vertical plane some distance from the fixed index —4— depending somewhat upon the amount of work which may be conveniently and economically carried on in the plant, but more particularly upon the amount of information 50 which the chart is required to give as to the various stages in the progress of the work.

For convenience of illustration of the operation of the chart I have shown only 55 three of the guides and a plurality of, in this instance five, information strips —a—, —b—, —c—, —c'— and —d— in each guide, but it will be evident from the following description, that the number of guides and 60 also the number of strips in each guide may be varied according to the information required.

The strips —a—, —b—, —c—, —c'— and —d— are preferably made in the form of 65 thin flat tapes of flexible card board or

equivalent material in different contrasting colors so as to be readily distinguishable one from another, and are relatively adjustable or slidable endwise in their respective guides by hand, or at will, so as to vary the 70 distances between corresponding ends at the front and thereby to indicate, by comparison of the exposed lengths, the condition of the work upon the articles corresponding to the title of any particular guide —1—.

The innermost tapes —a— are preferably secured by an adhesive, or otherwise, to the front faces of their respective guides and are provided with similar scales or numbered graduations gradually increasing in 80 value from left to right while the remaining tapes —b—, —c— and —d— are provided with scales or numbered graduations gradually increasing in value from right to left.

For example, assuming that the capacity 85 of output of a factory for a given period of time is 30,000 (more or less) machines of a certain type composed of, say three parts, such as a base, a left leg and a right leg, all 90 requiring some particular operation to enable them to be properly assembled in the completed machine, then the innermost strips are preferably graduated in this instance, in inches progressively increasing the values of 1,000 from left to right and each 95 division is divided into tenths, each representing one hundred parts so that the graduations will be numbered in sequence from left to right from 1,000 to 30,000 (29,000 100 being visible) with the ends of the innermost tapes representing the last named figure and vertically alined with each other.

The remaining tapes —b—, —c— and —d— represent similarly graduated and numbered strips from right to left with the 105 right hand end of each representing the lowest number.

One of the duties of the production manager is to see that a sufficient number of 110 parts are in stock and on order for the completion of a certain number of machines in a given time and in going over the stock or raw materials on hand, he finds that he actually has on hand 8,000 of the "Base" parts; 115 14,000 of the "Lf. Leg" parts and 12,000 of the "Rt. Leg" parts of which 4,000 of the "Base" parts, 4,000 of the "Lf. Leg" parts and 3,500 of the "Rt. Leg" parts are due on order.

This condition of the stock or raw materials would be shown on the chart by adjusting the strips or tapes —b— of the upper, intermediate and lower guides —1— endwise to the left to register their right hand ends with the 8,000; 14,000 and 12,000 120 graduations on said guides respectively, while the tapes or strips —c— of the same guides would be adjusted endwise to the left to bring their right hand ends into 125 registration with the graduations numbered 130

4,000; 4,000 and 3,500 on the tapes or strips —*b*— of the lower intermediate and upper guides respectively to indicate that of the 8,000 base parts 14,000 "Lf. Leg" parts and 5 12,000 "Rt. Leg" parts in stock and on order, 4,000 of the "Base" parts; 4,000 of the "Lf. Leg" parts and 3,500 of the "Rt. Leg" parts are still due on order and that the actual 10 number of each of those parts on hand upon which work can be immediately begun will be the difference between what is shown to be on order and the total amount of stock on hand and on order or, in this instance, 4,000 of the "Base" parts; 10,000 of the "Lf. Leg" parts and 8,500 of the "Rt. Leg" parts.

These parts which are actually on hand will therefore, be placed in the factory to receive any operations thereon which may be necessary in the process of manufacture and 20 to enable them to be installed in the assembling room for completing the machine.

These operations are defined as "under process" of finishing and in order to chart the numbers of articles or parts actually 25 under process, the strips or tapes —*d*— will be adjusted endwise to the left to register their ends with the numbers of those parts on the tapes or strips —*c*—.

For example, if 1,500 of the "Base" parts; 30 8,000 of the "Lf. Leg" parts and 7,500 of the "Rt. Leg" parts have been placed under process of finishing, the right hand ends of the tapes *d* of the uppermost, intermediate and lower guides will be adjusted to register with the graduations number 1,500; 8,000 and 7,500 of the underlying tapes —*c*—, respectively.

These adjustments of the several strips —*d*— will cause certain graduations thereon 40 to register with the fixed index —4— and the numbers of these graduations will indicate the number of each of the parts actually on hand and yet to be placed under process of completion of corresponding guides or as 45 illustrated, 2,500; 2,000 and 1,500 on the uppermost, intermediate and lower strips —*d*— respectively.

These numbers added to the readings on the strips —*c*— of the corresponding guides 50 will give the actual number of parts on hand and in process of construction or the sums of the readings on the strips —*d*—, —*c*— and —*b*— will correspond to the readings on the strips —*a*—.

In like manner, any number of strips may be used in each guide to give additional information as to the progress of the work from the raw material to the finished machine and by making the strips for each 60 guide of contrasting colors enables the production manager and others to see at a glance the relative progress of the work on any particular part by comparing the exposed lengths of the strips, one with another 65 irrespective of the reading of the graduations,

which is intended to give an accurate account of the number of parts in each progressive stage of manufacture, from the quantity in stock and on order to the finished machines, which latter would be indicated 70 by the registration of the right hand ends of all of the strips —*d*— with the fixed index —4—.

While Figure 1 shows only four exposed strips —*a*—, —*b*—, —*c*— and —*d*— in each 75 of the guides —1—, each guide actually contains five strips, an extra strip as —*c'*— making five in all for each section as shown in Figures 2 and 3, but the right hand ends of the strips or tapes —*c'*— are concealed by 80 the superposed strips —*c*— in that its right hand end is registered with that of the last named strip.

This extra strip —*c'*— may be used for other purposes than shown, as for example 85 to indicate one of the steps in the process of manufacture of each of the parts.

By the use of a chart of this character, the production manager or any other person interested, may readily determine the various 90 stages of manufacture of any one of the parts and also whether the department operating upon a quantity of any one of the parts is keeping pace with the progress of manufacturing of a quantity of any one of the 95 other parts in some other department and if not, the fault or delay may be quickly remedied either by supplying the necessary parts for manufacture or by speeding the operatives in the delayed department all of which 100 contributes greatly to the harmonious operation of the several departments operating upon different parts and assures the supply of the finished parts necessary to keep the assembling room in harmonious operation 105 and full capacity production.

I claim:

1. A progress chart comprising a plurality of strips relatively adjustable endwise at will one over the other to vary the distance between corresponding ends of the strips and thereby to indicate progressive stages of a working process, the rearmost strip and its overlying strip being provided with reversely arranged lengthwise scales.

2. A progress chart comprising a plurality of strips relatively adjustable endwise at will one over the other to vary the distance between corresponding ends of the strips and thereby to indicate progressive stages of a working process, each strip being provided with a lengthwise scale, and a fixed index 115 for cooperating with the outermost scale.

3. A progress chart comprising a guide, and a plurality of strips relatively adjustable endwise at will one over the other in said guide and each provided with a lengthwise scale, the innermost strip being fixed to said guide, and a fixed index cooperating 125 with the outermost scale.

4. A progress chart comprising a plurality of parallel guides designated by distinct but related titles, each guide containing a plurality of strips relatively adjustable end-
wise therein toward and from one end thereof and each strip graduated lengthwise to cooperate with one end of the next adjacent

strip for indicating the progressive stages of work under the title of the corresponding guide.

10

In witness whereof I have hereunto set my hand this 1st day of December 1923.

RAYMOND G. RECH.
